TOP FOR A DRUM STAND

Josephus B. Thompson, deceased, late of Covington, Ohio, by K. E. Stade, administrator, Covington, Ohio, assignor to Columbia Broadcasting System, Inc., New York, N.Y., a corporation of New York

Filed Oct. 9, 1968, Ser. No. 13,917

Term of patent 14 years

Int. Cl. D17—04

U.S. Cl. D56—1

Des. 218,258

PAGE 2

FIG. 2

FIG. 3.

FIG. 5.

FIG. 6.

FIG. 1 is a perspective view of a top for a drum stand, showing a new design;

FIG. 2 is a side elevational view, the opposite side being substantially a mirror image thereof;

FIG. 3 is a front elevational view;

FIG. 4 is a bottom plan view partly in cross-section taken on line 4—4 in FIG. 1;

FIG. 5 is a top plan view; and

FIG. 6 is an enlarged fragmentary perspective view of the hub portion of the stand top.

What is claimed is:

The ornamental design for a top for a drum stand, substantially as shown and described.
